[57] CLAIM

The original design for a games racket stringing network, as shown and described.

DESCRIPTION

FIG. 1 is a front view of the games racket stringing network of my new design;

FIG. 2 is a left side view thereof;

FIG. 3 is a right side view thereof;

FIG. 4 is a top view thereof;

FIG. 5 is a bottom view thereof; and,

FIG. 6 is a perspective rear view thereof.

The racket frame is shown in broken lines for illustrative purposes only and forms no part of the claim.

FIG. 2

FIG. 1

FIG. 3

FIG. 4

FIG. 5

FIG. 6
